Kevin Prince(57) **CLAIM**

The ornamental design for a vial with cone bottom, as shown and described.

DESCRIPTION

FIG. 1 is a front elevational view of a vial with cone bottom, showing my new design, the rear elevational view, left-side elevational view, and right-side elevational view all being identical thereto;

FIG. 2 is a top plan view thereof;

FIG. 3 is a bottom plan view thereof; and,

FIG. 4 is a cross-sectional view thereof, taken along line 4-4 of FIG. 1.
